UNITED STATES PATENT OFFICE

HENRY TRENCHAM, OF RUISLIP, AND HERBERT C. HEATH, OF WEMBLEY, ENGLAND,
ASSIGNORS TO GENERAL ELECTRIC COMPANY, A CORPORATION OF NEW YORK

ELECTRIC CIRCUIT BREAKER

Application filed April 30, 1931, Serial No. 534,062, and in Great Britain May 12, 1930.

Our invention relates to electric circuit breakers, more particularly to mechanism for effecting the tripping operation of circuit breakers in response to an abnormal or predetermined electrical condition in the circuit.

The conventional method of tripping oil circuit breakers includes the use of current transformers or low voltage tripping coils which in turn coat with mechanical tripping mechanism causing opening movement of the circuit breaker. However, under certain operating conditions, as where the circuit must be cleared within a very short time, it may be desirable to introduce a direct acting trip so as to decrease the time of the tripping operation.

In accordance with the present invention, in a circuit breaker or a combination circuit breaker and fuse capable of being tripped open by the collapse of an operating toggle mechanism the tripping impulse is transmitted directly to the toggle mechanism through the movable switch member serving to connect the stationary contacts of the switch in the closed circuit position, thereby simplifying the tripping mechanism and eliminating unnecessary tripping linkages.

In carrying the invention into effect, one of the so-called "fixed" or "stationary" contacts of the switch is mounted so as to have a limited degree of movement so that the tripping operation is accompanied by an initial movement in the circuit closing direction of the movable switch member coacting with the aforesaid contact, this initial and concurrent movement causing collapse of the toggle mechanism and consequent opening movement of the breaker. The portion of the toggle mechanism operatively connected to the movable switch member for actuating the same into engagement with the stationary contact is preferably arranged to continue its circuit closing movement after the switch member has engaged the stationary contact and come to rest, this continued movement causing compression of a spring further biasing the switch member into engagement with the stationary contact and thereby causing the aforesaid initial movement of the switch member when a tripping device controlling

the movement of the stationary contact is actuated.

The control of the limited movement of the stationary contact may be effected by a current responsive device as a fusible element connected in series with the switch contacts or by means of an electromagnetic current responsive device. For the purpose of relieving the fusible element, when such is employed, of the tension necessary to maintain the stationary contact in position against the bias of the spring above referred to, there is preferably provided a toggle having one of its links pivoted to the stationary contact and another to a fixed point, the fusible element passing over the common pivot of the two links of the toggle thereby restraining collapse of the toggle. In the case where an electromagnetically controlled tripping device is used to restrain the movement of the stationary contact a toggle may also conveniently be employed, the toggle being slightly overset in the closed position of the switch, and collapse thereof is caused by actuation of the tripping device whereby limited movement of the stationary contact takes place with consequent tripping of the toggle mechanism by the tripping impulse transmitted directly by the switch member. The movable switch member may be pivotally connected at one end to one of the stationary contacts having no limited movement or may take the form of a bridging member pivotally attached at its central portion to an operating rod for making and breaking the circuit at the stationary contacts in a well known manner.

Our invention will be more fully set forth in the following description referring to the accompanying drawings, and the features of novelty which characterize our invention will be pointed out with particularity in the claims annexed to and forming a part of this specification.

Referring to the drawings, Fig. 1 is an elevational view, partly in section, of a circuit breaker in the closed circuit position embodying our invention; Fig. 2 is an enlarged fragmentary view showing in detail the tripping arrangement illustrated in Fig. 100

1; Fig. 3 is a view of the circuit breaker shown in Fig. 1 in the open circuit position thereof; Fig. 4 is an elevational view, partly in section, of a modified form of tripping mechanism in the closed circuit position; Fig.

5 is a similar view showing the apparatus in the open circuit position, and Fig. 6 is a view similar to Figs. 4 and 5 showing a modification of the movable switch member.

10 Referring to the arrangement shown in Figs. 1 to 3, there is illustrated an oil circuit breaker comprising a stationary contact 10 and a conducting element 11 carried at the lower ends of the insulating bushings 12 and 13 respectively which extend through and are supported in the housing 15 of the circuit breaker. The members 10 and 11 in closed circuit position are electrically connected by the movable switch member 16 carrying the 15 movable contact coating with contact 10 and in the present instance pivoted at one end to the conducting element 11 and operatively connected through the insulating operating rod 17 to the operating mechanism likewise 20 mounted within the housing 15. The operating mechanism comprises a bellcrank lever 18, to one arm of which the rod 17 is connected, pivotally mounted at 19 with respect to the housing 15 and biased in a counter-clockwise direction by the opening spring 20 which is connected at one end to the housing 25 as at 21 and at the other end to an arm of the bellcrank as at 22.

Movement of the bellcrank lever to cause 30 opening and closing of the circuit breaker is effected through a toggle mechanism comprising the links 23, 24 and 25. The link 23 is pivotally connected, as at 26, to the arm 22 of the bellcrank 18 and to the link 24 at the 35 point 27. The link 25 is in turn pivotally mounted at 28 on the housing 15 and at its other end is pivotally connected at 29 to the link 24. For the purpose of manually operating the circuit breaker the link 25 is provided with a suitable operating lever 30 mounted externally of the switch housing. For the purpose of maintaining the toggle 23-24-25 in a slightly overset position for restraining the switch member in the closed 40 circuit position the link 24 is provided with a pin 31 arranged to be engaged by the over-hanging end 32 of the link 23.

The insulating rod 17 is suitably attached at its lower end to the movable switch member 16 and is resiliently connected at its upper end to the bellcrank 18. The upper extension 17' of the rod 17 extends through an opening in the pin 32, carried by the bellcrank 18 and is provided at its upper end with a collar or shoulder 33 between which and the pin 32 a spring 34 is positioned so that the rod 17 has both sliding and pivotal movement with respect to the bellcrank 18.

45 The insulating rod 17 likewise is provided with an abutment 35 which, when the rod 17

is moved upwardly under the influence of spring 34, as will be hereinafter described, engages an extension 36 of the link 24 causing the toggle comprising the links 23 and 24 to collapse.

50 The tripping device controlling limited movement of the contact 10 is illustrated more clearly in Fig. 2 wherein the contact 10 is shown pivotally mounted at 37 on a collar 38 carried by an extension of the insulating bushing 12. Mounted also upon the collar 38 is a toggle comprising links 39 and 40, the link 40 being pivotally connected to the overhanging end 41 of contact 10 and the link 39 being pivotally connected at 42 to the collar 38, the two links having a common pivotal connection 43. As illustrated in Fig. 2, the toggle is shown in the closed circuit position, the tripped or open circuit position being 55 illustrated by dotted lines. The contact 10 is maintained in the position shown in Fig. 1 by a fusible element or link 44 connected at 45 to the corresponding conductor stud of the circuit breaker, the link passing over the common pivot 43 of the toggle and attached 60 at 46 to the contact 10.

65 The operation of the circuit breaker is as follows: In the closed circuit position illustrated in Fig. 1 the springs 20 and 34 are both under tension, the spring 20 tending to cause 70 the bellcrank 18 to move in a counterclockwise direction to lower the rod 17 to open circuit position, whereas the spring 34 tends to move the rod 17 in an upward or circuit closing direction. This later movement however is restrained by the toggle 39-40 and the fusible element 44 which is placed under tension and prevents collapse of the tripping toggle. In response to a predetermined or 75 abnormal circuit condition, as overload, the current flowing through the fusible element 44 in series with the breaker contacts causes the fusible element to blow so that rupture thereof permits the toggle 39-40 to collapse to the dotted line position under the influence of the spring 34. The initial movement of the switch member 16 in a clockwise direction thus instituted moves the abutment 80 35 sharply into engagement with the extension 36 of the toggle link 24 causing collapse of the toggle and consequent opening movement of the breaker under the influence of the opening spring 20 to the position illustrated in Fig. 3.

85 The closing operation of the circuit breaker must be preceded by replacement of the fusible element, whereupon the toggle 23-24 may be straightened by rotating the operating handle 30 in a counterclockwise direction and then moving it in a clockwise direction to rotate the bellcrank member 18 clockwise. During this movement the switch member 16 90 engages the contact 10 so that subsequent movement of the bellcrank causes only com- 95

pression of the spring 34 to the position illustrated in Fig. 1.

It will be noted that the arrangement of the toggle 39-40 in a slightly underset position 5 relieves the fusible element 44 of considerable tension which it would otherwise have to bear if it alone were required to restrain the movement of contact 10 against the bias of the spring 34.

10 Referring now to Figs. 4 and 5, the arrangement shown is generally similar to that shown in Figs. 1 and 2, and does not require detailed description except insofar as the tripping mechanism is concerned. In this 15 case, the tripping device is controlled electromagnetically instead of by a fusible element, as in Figs. 1 and 2. The contact 10 is pivotally mounted on the member 47 carried by the insulating member 48 at the lower end of the 20 bushing 12. The member 48 furthermore carries a magnet 49 having a coil 50 and an armature 51 of bellcrank shape, pivoted at 52' to the member 47. The coil 50 is included 25 in series with the switch contacts in the circuit controlled by the breaker. The counterclockwise rotation of the contact 10 about its pivot is restrained by the toggle comprising 30 links 52 and 53 which, in the closed position of the circuit breaker, are slightly overset, as shown. On a predetermined overload occurring 35 in the circuit, armature 51 is attracted to the magnet 49, and the arm 54 of the armature 51 strikes the common pivot of the links 52 and 53, causing the collapse of the toggle 40 and the opening of the breaker in the manner described in connection with Figs. 1 and 2. The position of the various parts of the circuit breaker in the tripped-open position are as shown in Fig. 5. On the opening of the 45 circuit breaker, the armature 51 is no longer attracted, thereby permitting the contact 10 to rotate in a clockwise direction under the action of gravity so that the toggle comprising links 52 and 53 becomes straightened, as shown in Fig. 5.

In Fig. 6 there is shown an arrangement having an electromagnetically operated tripping device similar to that described in connection with Figs. 4 and 5. The only difference in this particular construction is that 50 instead of the switch member 16 being pivoted to the member 11, it is pivotally arranged upon the insulating rod 17. In this case, upon the tripping open of the circuit breaker 55 by the limited movement of contact 10, the switch member 16 is permitted to slide on the contact surfaces of the contact 10 and member 11 about its fulcrum on the insulating rod 17 to the position shown in dotted lines in Fig. 6, whereupon the breaker is tripped open as 60 described in connection with Figs. 4 and 5. Preferably, the switch member 16 is arranged to have only a limited pivoting movement upon the insulating rod 17.

65 In all the figures the insulating rod 17 has

been shown as comprising upper and lower metallic members attached through an insulator which may be of porcelain or any other suitable material. It is to be understood, however, that any other construction of the insulating rod 17 is permissible provided the switch member is insulated from the toggle operating mechanism. The various links of the toggle operating mechanism usually comprise a pair of parallel members suitably spaced from one another, spacing members serving to provide the necessary pivot points about which the various links co-act.

70 It is also to be understood that the invention has been described only in connection with a single phase breaker, but the invention may be employed in connection with polyphase circuits. In this case the tripping open of the circuit breaker on any one phase 75 may be arranged in a well known manner to trip open the breaker situated in the other phases of the circuit.

75 It should be understood that our invention is not limited to specific details of construction and arrangement thereof herein illustrated, and that changes and modifications may occur to one skilled in the art without departing from the spirit of our invention.

80 What we claim as new and desire to secure by Letters Patent of the United States, is:

85 1. An electric circuit breaker comprising 90 a movable switch member, coacting contacts controlled thereby, operating mechanism restraining said switch member in the closed circuit position, and means responsive to an abnormal circuit condition causing an initial movement of said switch member in the switch closing direction, said initial movement causing collapse of said operating mechanism and 95 circuit opening movement of said switch member.

100 2. An electric circuit breaker comprising 105 a movable switch member, contacts coacting therewith, an operating toggle restraining said switch member in the closed circuit position, and means responsive to an abnormal circuit condition causing an initial movement of said switch member in a closing direction independently of said operating toggle, said 110 initial movement causing collapse of said operating toggle and circuit opening movement of said switch member.

115 3. An electric circuit breaker comprising 120 a movable switch member, a contact mounted for limited movement coacting therewith, means biasing said switch member into engagement with said contact, toggle operating means maintaining said switch member in closed circuit position, means responsive to an abnormal circuit condition causing limited movement of said contact and said switch member independently of said operating means, and an operative connection between 125 said switch member and toggle means causing collapse of said toggle and opening move- 130

ment of said switch member in response to said limited movement.

4. In an electric circuit breaker including a movable switch member, a cooperating contact mounted for limited movement and operating mechanism collapsible to cause circuit opening movement of said switch member, tripping means for said breaker comprising means maintaining said contact in a 10 limiting position, a resilient connection between said switch member and operating mechanism biasing said switch member into engagement with said contact in the closed circuit position tending to cause movement 15 of said contact, current responsive means for causing release of said contact and initial movement of said switch member through said resilient connection, and means actuated in response to said initial movement of said 20 switch member causing collapse of said mechanism and circuit opening movement of said switch member.

5. Tripping mechanism for an electric circuit breaker having a movable switch member, operating mechanism collapsible to cause circuit opening movement of said member and a contact coacting with said switch member, said contact mounted for limited movement, comprising a current responsive device 25 normally maintaining said contact in a predetermined position, means resiliently biasing said switch member into engagement with said contact tending to move said contact into another position, release of said 30 contact in response to actuation of said current responsive device causing limited movement of said switch member independently of said operating mechanism under influence of said biasing means, and means connected 35 to said switch member directly causing tripping of said collapsible mechanism and circuit opening movement in response to said limited movement.

6. An electric circuit breaker comprising 45 a movable switch member, a contact mounted for limited movement coacting therewith, overset toggle operating mechanism restraining said switch member in closed circuit position, an opening spring for biasing said 50 switch member to open circuit position in response to tripping of said toggle mechanism, means interconnecting said switch member and operating mechanism resiliently biasing said switch member independently of 55 said opening spring into engagement with said contact in the closed circuit position, means arranged to release said contact in response to an abnormal circuit condition, said 60 resilient biasing means thereby causing an initial movement of said switch member in the circuit closing direction independently of 65 said toggle operating mechanism, and means connected to said switch member causing tripping of said mechanism and circuit 70

opening movement in response to said initial movement.

7. An electric circuit breaker comprising a movable switch member and a contact mounted for limited movement coacting therewith, toggle operating mechanism operatively connected through an insulating rod to said switch member, said toggle mechanism having a resilient connection with said rod arranged so that said resilient connection is stressed in the circuit closing operation, an opening spring tending to bias said toggle mechanism towards open circuit position, and tripping means comprising a current responsive device coacting with said contact arranged so that actuation of said device releases said contact for limited movement and causes corresponding movement of said switch member through said resilient connection, and a member connected to said rod causing tripping of said toggle in response to said movement.

8. In an electric circuit breaker including a movable switch member and a contact coacting therewith, said contact mounted for limited movement, and operating mechanism collapsible to cause circuit opening movement of said switch member, tripping means comprising a fusible element normally restraining said contact in a predetermined position, means resiliently biasing said switch member into engagement with said contact arranged so that rupture of said fusible element causes release of said contact and an initial movement of said switch member independently of said operating mechanism, and means connected to said switch member causing collapse of said operating mechanism and circuit opening movement in response to said initial movement.

9. In an electric circuit breaker including a movable switch member and a contact coacting therewith, said contact mounted for limited pivotal movement and toggle operating mechanism collapsible under the influence of an opening spring to cause circuit opening movement of said switch member, tripping means for said toggle mechanism comprising a fusible element connected in series with the circuit breaker normally restraining movement of said contact, an underset toggle connected to said contact and engaged by said fusible element arranged so that the restraining force is borne mainly by said toggle, a resilient connection between said switch member and toggle mechanism stressed in the closed circuit position to bias said switch member into engagement with said contact whereby rupture of said fusible element causes release of said contact and an initial movement of said switch member through said resilient connection, and means actuated in response to said initial movement of said switch member directly causing trip-

ping of said toggle mechanism and circuit opening movement.

10. In an electric circuit breaker including a movable switch member, a contact mounted for limited movement coacting therewith, an operating toggle having a resilient connection with said switch member, said resilient connection biasing said switch member into engagement with said contact in the closed circuit position of said member, and an electromagnetic current responsive device coacting with said contact arranged so that actuation of said device releases said contact and causes limited movement of said switch member in the closing direction under influence of said resilient connection, and means connected to said switch member causing tripping of said operating toggle in response to said movement.
15. 11. An electric circuit breaker comprising a pair of coacting contacts, operating mechanism for controlling said contacts, means responsive to an abnormal circuit condition causing initial and concurrent movement of said contacts, and means responsive to the aforesaid initial movement of said contacts causing circuit opening movement of said operating mechanism.
20. 12. An electric circuit breaker comprising a movable switch member, coacting contacts controlled thereby, operating mechanism including a tripping toggle for restraining said switch member in the closed circuit position, and means responsive to an abnormal circuit condition causing an initial movement of said switch member, said switch member tripping said toggle during said movement causing circuit opening movement of said operating mechanism and switch member.
25. 40. In witness whereof, we have hereunto set our hands.

HENRY TRENCHAM.
HERBERT C. HEATH.
